UNITED STATES PATENT OFFICE.

JOSEPH H. COHEN, OF BRIDGEPORT, CONNECTICUT.

AUTOMATIC ELECTRIC SWITCH FOR CABLE-CARRYING DRUMS.

Application filed November 3, 1923. Serial No. 672,630.

This invention relates to certain new and useful improvements in automatic electric switches for cable-carrying drums, of that general type employed in connection with 5 cigar lighters, for use on motor vehicles, or any other place, or for other devices which are supplied with an electric current through a flexible carrier carried upon a self-winding drum or reel through parts of which the 10 electrical current is passed.

The present invention, has for its objects among others to provide a simple, efficient, and dependable device of this nature, capable of general use, not liable to get out of 15 order, embodying in its make-up a minimum number of parts consistent with positive and reliable results, capable of production at small cost, and readily assembled.

Other objects and advantages of the invention 20 will hereinafter appear and the novel features thereof will be particularly pointed out in the appended claims.

Broadly considered, the invention embodies a spring drum with a cord or cable 25 attached thereto to be wound thereon or unwound therefrom, said cable serving as a current conducting wire or means, and the drum carried by a revolute screw-threaded member which constitutes a helical cam and with which coacts a non-rotatable member, 30 as a nut, this non-rotatable member flexibly carrying a current-carrying member controlled in its movements by the movement of the nut toward and from the drum and serving in conjunction with the drum as a contact member by making a brush-like engagement 35 with the adjacent face of the drum to make an electrical connection with a current-carrying portion of the drum so as to close the circuit. The degree to which the cable 40 must be drawn out to close the circuit may be varied as circumstances may require and may be predetermined by the pitch and fineness of the threads on the nut and its co-operating member movable with the drum.

The invention, hereinbefore briefly stated, 45 is capable of embodiment in a variety of forms, a number only of which are herein illustrated, but which serve to show several practical embodiments of the invention.

The invention, in such preferred forms, is clearly illustrated in the accompanying drawings, which, with the numerals of reference marked thereon, form a part of this 50 specification, and in which

Figure 1 is a substantially central section

taken axially through the device with parts in elevation.

Figure 2 is a section as on the line 2—2 of Figure 1, looking in the direction of the 60 arrow.

Figure 3 is an enlarged sectional detail with parts in elevation, but with the nut and the parts carried thereby shown in different positions. 65

Figure 4 is a detail section taken parallel with the axis of the drum, showing a modified form.

Figure 5 is a section on the line 5—5 of Figure 4, looking in the direction of the 70 arrows.

Figure 6 is a view similar to Figure 4, showing another form of embodiment of the invention. 75

Figure 7 is a perspective view of the contact-carrying nut removed and with the contact member omitted.

Like numerals of reference indicate like parts throughout the several views.

Referring to the drawings, 80
1 designates a suitable casing or housing within which is rotatably mounted the drum or reel, and in which are located the other parts of the device except the current-consuming device 2, shown conventionally in Figure 2, and which may be a cigar lighter such as is usually employed in this class of devices, or it may be a lamp, the cord or cable 3 connected with the element 2 in the usual way being extended through an opening 4 in the wall of the housing 1, and in the present instance, Figure 2, being shown as passed through the socket or bushing 5 clamped to the member 6 which may be the dash or other portion of a motor vehicle, 7 and 8 designating the nuts upon the screw-threaded member 5 for an obvious purpose. 85
90
95

The drum or reel construction preferably includes two metallic discs or head flanges 9 and 10 fixedly mounted upon a hub 11, the disc 9 being insulated from the hub by an insulating collar 12, and the two discs insulated from each other by the fibre or other disc 13 surrounding the hub, and, upon which is wound the wire or cable 3, as seen in Figure 1. The hub 11 has a collar 14 fitted within an axial opening in the disc or head 10, as seen in Figure 1. 15 is a fibre or other insulating collar or washer surrounding the hub 11, against which bears a metallic collar 16 retained by suitable member 17, 100 as seen in Figures 1 and 3. 105
110

The disc or member 10 is provided with an annular flange 18 within which is housed the spring 19, see Figure 1, one end of said spring being fixed in any well-known way 5 to said flange, and the other end affixed, as at 20, to the bolt or the like 21 mounted at one end in the hub 11, and the other end carrying a screw 22 mounted in a bearing 23 in one wall of the housing 1, as seen in 10 Figure 1. Other means, however, of mounting this end of the hub may be resorted to, and any suitable means may be employed for attaching this end of the spring.

The screw-threaded member 25 is mounted 15 in a suitable bearing 27 on the wall 28 of the housing, its other end being rigid with the hub 11, so as to rotate with the drum.

29 is a member having an axial opening 30 internally threaded, as at 31, see Figure 7, 20 for cooperation with the threaded member 25. This member 29 is non-rotatable but is mounted for movement toward and away from the disc or drum flange 9, and, in the present instance, is guided in such movements by the guide members 32 extended loosely through the openings 33 in the ears 34 of the nut 29, see Figures 1 and 3.

35 is a member of metal secured to the face of the nut 29 by any suitable means, 30 such as 36, see Figure 1, and to this member 35 is soldered or otherwise affixed one end of a coiled spring 37, the other end of which is soldered or otherwise affixed to the member 38, from which extend parallel with the 35 member 25, or substantially so, a plurality of contacts 39, the number of which may be varied, as found most expedient, and which are designed for contact with the disc 9 under predetermined conditions, as will soon 40 be explained.

40 are binding posts equipped with nuts and of usual form supported in the housing 1, as seen in Figures 1 and 2.

41 is a wire leading from a battery and 45 connected up with one of the binding posts 40, as seen in Figures 1 and 3. 42 is a wire connected with the other binding post and leading to ground.

43 is a wire leading from the binding post 50 connected to battery and the other end of this wire is connected with the metal member 35 carried by the traveling nut 29.

The operation will be clear from the foregoing description when taken in connection 55 with the annexed drawings. Briefly stated, it is as follows:—Normally the cable or wire 3 is wound upon the drum. When the member 2 is grasped to pull the cable out, the drum is revolved against the tension of its 60 spring. Normally the contact points 39 are out of contact with the adjacent face or flange of the drum, as seen in Figure 1, the spring 37 being expanded, as shown, and the circuit is broken. The cable is pulled out 65 a foot, more or less, as may be previously

determined, before contact is made to complete the circuit. By this means I provide for positive assurance that the current will be shut off until the cable has been drawn out a certain distance and also make sure 70 that the current will not be left on in case the member 2 is not fully returned to its normal position. As the cable is further drawn out the contact members 39 are moved into engagement with the adjacent face of 75 the member 9 and the circuit is completed, and the member 2 is energized. It is to be noted that the disposition of the spring, the nut and the contacts is such that as the nut 80 is advanced by reason of the rotation of the drum the contacts are first forced into engagement with the disc 9 under relatively light tension, but as the nut is further moved the tension of the spring increases, and by this means even when the parts have been 85 in long continued use and become worn there will be positive contact. Figure 3 shows the position of the parts when the contacts have been forced against the member 9 by the movement of the nut through the rotation 90 of the drum. The make and break is positive, and possibility of short circuiting is avoided; the action is of necessity positive and the same in every instance being controlled positively by the rotation of the 95 drum, either when the cable is wound or being unwound. The positive action is not dependable upon the spring. As the member 2 is released, the cable is wound upon the drum and the nut is moved in the opposite direction through positive connection with the screw member 25 and the contacts are moved out of engagement with the member 9, as will be readily understood.

It will be noticed that the construction 105 is such that the contact nut and the parts carried thereby remain practically dormant, after the circuit is broken, during the rewind of the drum, for as soon as the member 2 is returned to its normal position the contacts 110 are moved out of engagement with the member 9, and thus remain inactive until the member 2 is again pulled out sufficiently to bring the said contacts into contact with the member 9 to complete the circuit and 115 energize the member 2.

It may sometimes be found desirable to provide means for guiding the member 38 which carries the contacts 39. In such case I may provide such member 38 with fibre 120 or other insulating guide members 44, as seen in Figure 3, these members having openings for the free passage of the guide rods 32.

The cable has one strand soldered or otherwise affixed to the disc 10 leading to ground and the other strand is connected by solder or otherwise to the disc 9 connected to battery.

The bolt 21 serves as a fixed shaft for the 125

drum and also as a means whereby the end of the spring may be affixed in position.

Figure 4 shows a different form of embodiment of the invention, but involving the same generic features. In this form the disc 45 of the drum is provided upon its face adjacent the contact-carrying nut with a plate or disc 46 of insulating material. The hub 47 is insulated from the disc 45 by suitable insulation 48 and further from the disc 45 by the insulating collar 49, 50 being a metal collar bearing against the collar 49 and 51 being the member holding the said collar in place. 52 is the screw shaft carrying the drum and the end of this has a bearing in the wall 53 of the housing, as seen at 54. 55 and 56 are the binding posts for the connection of the wires the same as in the form shown in Figures 1 and 3. 57 and 58 are guide rods carried by the wall of the housing and freely slideable through openings 59 in the nut 60.

61 is a wire leading from battery to the binding post 55, while 62 is a wire leading from the outer binding post 56 to ground. 63 is a wire leading from the binding post 55 to the metal spring member 64 which is secured to the face of the nut 60, as seen in Figure 4 at 65. This spring is arched, as shown, its ends being designed to normally engage the insulating member 46, as indicated by full lines in Figure 4.

It is to be understood that the parts are connected up the same as in Figures 1, 2 and 3, the cable being wound upon the drum, which is spring-actuated as before, and the nut controlled in its movements by the revolution of the drum. Normally the ends of the spring 64 are in engagement with the insulating member 46, as shown by full lines in Figure 4, the other parts being in the position shown by full lines in the said Figure 4. Now, when the member 2 is pulled upon, the cable will be drawn out from the reel, and the reel or drum thereby revolved, the ends of the spring remaining in contact with the said insulating member until there has been a foot more or less, as may be previously determined, drawn out. During this time, of course, the current is shut off, the circuit being broken. As more of the cable is pulled out, the nut is moved further toward the adjacent flange of the drum or reel and the spring 64 is caused to spread so that its ends will be moved out of contact with the insulating disc and will then engage the metal portion of the drum flange or disc and the circuit will be completed and the member 2 energized. As the drum re-winds, the nut is moved in the opposite direction and the spring returns to its normal position, with its ends in contact with the insulating disc and the current is shut off.

In the form shown in Figure 6, the structure is quite similar to that just described

in connection with Figure 4, except that the insulating disc on the drum flange is omitted, and the spring 66 carried by the nut 67, which latter is guided in the same way as in the other forms, instead of having its ends normally in contact with the drum flange has such ends normally out of contact therewith, as seen in said Figure 6, so that under normal conditions the circuit is broken. The spring is arched as before and is attached to the nut by any suitable means, as at 68. As the cable is drawn out, it moves the predetermined distance without the ends of the spring contacting with the drum disc. After the cable has been pulled out the predetermined distance, the ends of the spring will be brought up against the disc 45 by the movement of the nut and the circuit closed and the member 2 energized. On the rewind, the nut moves away from the drum disc and the spring leaves the latter and shuts off the current. The spring is connected with the binding post by wire 69, the binding posts being connected with battery and ground as in the other forms.

Modifications in detail, proportion and relative arrangement of parts may be resorted to without departing from the spirit of the invention or sacrificing any of its advantages.

What is claimed as new is:—

1. A take-up device for current-carrying cables, comprising a current carrier take-up drum on which the cable is wound and to which the cable is electrically connected, the drum having a contact member forming a necessary structural part of it; and a co-operating contact member disposed axially of the drum and adapted to carry current and movable toward and from the drum in a direction parallel to the axis thereof through the rotation of the drum to electrically engage and disengage the said contact member which forms a necessary structural part of the drum.

2. A take-up device for current-carrying cables, comprising a drum casing provided with a cover plate; a take-up drum mounted in the casing; a current-carrying contact member movable axially of the drum into electrical engagement therewith; a rotary threaded element rotatable with the drum; a non-rotating threaded element cooperating with said rotary element to cause the contact to move into engagement with the drum when the drum is rotated to unwind the cable therefrom; and means for anchoring said non-rotating threaded element on said cover plate against turning movement.

3. A take-up device for current-carrying cables comprising a drum casing provided with a cover plate; a take-up drum mounted in the casing; a current-carrying contact member movable axially of the drum into electrical engagement therewith; a rotary

4
threaded element rotatable with the drum; a non-rotating threaded element cooperating with said rotary threaded element to cause the contact to move into engagement with the drum when the drum is rotated to unwind the cable therefrom, the non-rotating threaded element being adjustable with relation to the rotating threaded element so as to vary the extent of movement of the drum which is necessary to bring the contact into engagement with the drum; and means on the cover plate of the casing for anchoring the non-rotating threaded element against turning movement.

15 4. In a device of the character described, a cable-reel, two members, one a nut and the

other a screw associated with said reel, the nut and screw being one rotatable with respect to the other, means for rotating the rotatable one of said members as the cable 20 reel rotates so that, as a result of the screw-threaded engagement of the one member with the other, bodily movement of one of the members toward the reel is effected, a current carrying contact on the movable 25 member adapted to make electrical engagement with a contact on the reel when moved bodily toward the reel; and non-current-carrying means for holding the member which does not rotate against rotation. 30

In testimony whereof I affix my signature.

JOSEPH H. COHEN.
